UNITED STATES PATENT OFFICE.

CHARLES R. ALLEN, OF ASHTABULA, OHIO, ASSIGNOR TO THE ASHTABULA BOW SOCKET COMPANY, OF ASHTABULA, OHIO, A CORPORATION OF OHIO.

TOP FOR VEHICLES AND THE LIKE.

Application filed November 28, 1919. Serial No. 341,154.

To all whom it may concern:

Be it known that I, CHARLES R. ALLEN, a citizen of the United States, and a resident of Ashtabula, county of Ashtabula, and State of Ohio, have invented a new and useful Improvement in Tops for Vehicles and the Like, of which the following is a specification, the principle of the invention being herein explained, and the best mode in which 10 I have contemplated applying that principle so as to distinguish it from other inventions.

The present improved top belongs to the class of so-called "one man" tops in which 15 all of the top structure forwardly of a rear main bow or support is carried therefrom so as to eliminate the necessity for any forward main bow separately attached to the vehicle body. These tops might more properly be called "clear vision" tops, since 20 equally important with ease of manipulation is the provision of an unobstructed view for the occupants of the vehicle. The object of the present invention is to provide 25 a structure of this type which may be supported from a single rearwardly inclining main bow so as still more perfectly to realize the clear vision effect. A further object is to provide a structure that may 30 be readily manipulated either to fold or unfold the top as desired, while, by reducing to a minimum the number of operative parts, the manufacture is simplified and the cost correspondingly decreased.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:—

Fig. 1 is a side elevational view of a top supporting structure embodying my present improvements, such top being shown as 50 mounted on an automobile body or tonneau of conventional form; and Fig. 2 is a similar side elevation showing a modified form of construction.

It is of course a matter of indifference 55 whether the top is used on automobile,

motor-boat or otherwise, and, depending upon its longitudinal extent, a smaller or larger number of bows, in addition to the outrigger structure of present interest, may be utilized. It will also be understood that 60 the term "bow" is used herein inclusively to designate not merely the wooden bow proper, but also the metallic sockets carrying the same, these parts when regarded in side elevation constituting the equivalent of 65 the so-called "sticks," as they are called in the old wood structure. It is accordingly a matter of convenience to refer to the parts in the singular, as though the structure lay all in a single vertical plane, since the parts 70 of interest do actually lie in such a plane.

As previously indicated, the top covering 1 is designed to be entirely supported through an appropriate outrigger structure from a single main bow 2. The latter, which 75 is of substantial construction in view of the weight it is thus designed to carry, is pivotally supported upon or attached to the body at the point 2^a in the usual manner, so that it may be laid down and supported in a 80 substantially horizontal plane when the top is not in use. Normally, in the extended or open condition of the top, said main bow 2 inclines rearwardly at an angle of approximately forty-five degrees to the horizontal, 85 being held from rising higher by the top covering, or rather by special straps (not shown) or extensions of the longitudinal strainers which, as is well known, are used to connect the bows together and provide 90 supporting means for the top covering intermediately between said bows. For the purpose in hand such straps or strainers may be regarded as a part of the covering material.

Referring first to the features of construction common to both of the specific forms illustrated in the drawing, the outrigger structure which here constitutes all of the top supporting means save that supplied by 100 main bow 2 will be seen to comprise a pair of bows 3 and 4 pivotally connected together at the point 5. This point is approximately midway between the ends of said bows respectively, regarding the same in 105 side elevation, and it will be noted that the pivot in question is formed in a clamp 6 mounted directly on the upper face of the bow 3 in the extended condition of the top. The main portion of bow 4 accordingly lies 110

in the same plane with bow 3, and so is adapted to fold directly thereagainst when the top is collapsed and form a correspondingly compact stack. The inner or lower portion of said bow 4 consists of an extension 7 laterally offset with respect to such main portion so as to lie within the bow 3, as clearly shown in Fig. 1. The lower or inner end of bow 3 is connected with the corresponding side of main bow 2 by means of a link 8, the joint 9 between the parts in question being a rule joint disposed so as to prevent further bending of said parts when extended in the approximately horizontal position they occupy when the top is open. To the lower end or extension 7 of bow 4 is in turn attached the inner end of a forwardly extending or outrigger bow 10, the joint 11 here being likewise a rule joint which prevents further bending of the parts in question in an upward direction when the top is open or fully extended.

In the specific constructional form of my improved top illustrated in Fig. 1, I provide a link 12 extending from the same bracket 13 on main bow 2 by means of which a link or arm 8 is attached to said bow, to a point 14 on the inner end of bow 3 located a short distance in advance of joint 9. The point of attachment of this link 12 to the main bow is above that of said link or arm 8 to the latter, and the connection with bow 3 is preferably a sliding pivotal one as shown, and in addition it will be noted that, in the open or extended condition of the top, said joint 9 lies slightly above a straight line connecting such points of attachment of link 12 to the main bow 2 and bow 3, respectively. Link 12, it will accordingly be seen, serves to support the outrigger structure as a whole, acting as a tension member in the open condition of the top to rigidly sustain the bow 3 in alignment with arm 8. This link does not interfere in any way, however, with the folding operation, for, the moment joint 9 is broken and moved downwardly so as to fall below the line of said link, the top will immediately collapse, joint 11 simultaneously breaking downwardly. The disposition and relative location of the several joints in the structure are such that the outrigger bow will fold up against the front face of bow 3 when bow 4 folds against the rear face thereof, and all three are at the same time brought back against main bow 2 so that the structure as a whole may be dropped in a compact stack on the usual top rests (not shown).

The construction shown in Fig. 2 differs from that of Fig. 1 in the provision of modified means for rigidly supporting the bow 3 and arm 8, which together may be regarded as constituting an articulated bow.

In other words, instead of carrying a link

from the main bow to a point forwardly of joint 9 in such articulated bow, I connect the arm 8 with rearwardly extending supplemental bow 4 by means of a link 15, and then employ a link 16 which, as before, is attached at its rear end to bracket 13 at a point above the pivotal connection of said arm 8 therewith, and is attached at its forward end by means of a sliding pivotal connection 17 with said first named link 15. As a result of the double link construction just described, not only is the so-called articulated bow, consisting of bow 3 and arm 8, rigidly supported in desired position when the top is opened out, but the rearwardly extending supplemental bow 4 carried by said bow 3 is at the same time held in predetermined position. There is thus formed a self-sustaining frame structure, the outrigger bow 10 being obviously sustained in proper position by the action of rule joint 11 whereby it is connected with the lower extension 7 of supplemental bow 4.

The method of operation of this modified construction is substantially identical with that of the one first described, and should not require detailed explanation.

Both of the foregoing designs present numerous advantages over current types of one man or clear vision top construction. All of the bows, as well as supporting arms and links therefor, are carried well above the lower edge of the top cover 1, even where the quartering is shallow, as is necessary where it is desired to give the popular flat effect to the top. The top, in other words, may be made to approach more closely the lines of the completely rigid frame type of construction than with any other foldable form of support. Not only is such frame easily foldable, but to open or extend the top is an equally simple operation, for, upon raising the main bow 2, all that is necessary is to force bows 3 and 4 apart, which may be done either directly or by raising joint 11 and simultaneously pulling forward on the frame as a whole.

The articulated bow consisting of bow 3, proper, and the arm 8 supporting the same, may be properly regarded as one outrigger bow, while the bow 10 carried by the lower, forwardly extending end of supplemental bow 4, may be regarded as a second outrigger bow (sometimes called the "peak" bow). It will be understood that this last-mentioned bow is desirably secured to the windshield frame by detachable fasteners in the usual manner.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a top for vehicles and the like, the combination of a main bow; a foldable outrigger structure comprising a two-part articulated outrigger bow having its rear portion pivotally attached to said main bow, a rearwardly inclining supplemental bow pivotally attached to the forward portion of 5 said outrigger bow, the lower end of said supplemental bow extending forwardly beyond said outrigger bow, and a second outrigger bow pivotally attached to such extending end of said supplemental bow; and 10 a foldable linkage connecting said outrigger structure with said main bow and adapted to sustain said structure from said bow in the open condition of the top.
2. In a top for vehicles and the like, the combination of a main bow; a two-part articulated outrigger bow having its rear portion pivotally attached to said main bow; a rearwardly inclining supplemental bow pivotally attached to the forward portion of 15 said outrigger bow, the lower end of said supplemental bow extending forwardly beyond said outrigger bow; a second outrigger bow pivotally attached to such extending end of said supplemental bow; a link pivotally connecting said supplemental bow and 20 the rear portion of said first outrigger bow; and a second link connecting said first link with said main bow at a point above the point of attachment of said first outrigger bow thereto. 25

bow pivotally attached to such extending end of said supplemental bow; a link pivotally connecting said supplemental bow and the 30 rear portion of said first outrigger bow; and a second link connecting said first link with said main bow.

3. In a top for vehicles and the like, the combination of a main bow; a two-part articulated outrigger bow having its rear portion pivotally attached to said main bow; a rearwardly inclining supplemental bow pivotally attached to the forward portion of 35 said outrigger bow, the lower end of said supplemental bow extending forwardly beyond said outrigger bow; a second outrigger bow pivotally attached to such extending end of said supplemental bow; a link pivotally connecting said supplemental bow and 40 the rear portion of said first outrigger bow; and a second link connecting said first link with said main bow at a point above the point of attachment of said first outrigger bow thereto. 45

Signed by me, this 26 day of November, 50
1919.

CHARLES R. ALLEN.
